UNITED STATES PATENT OFFICE.

JAMES A. MOORE, OF ROCHESTER, AND JAMES S. CONLEY, OF BEAVER, PENNSYLVANIA.

SPACING MECHANISM.

Application filed July 29, 1924. Serial No. 728,894.

To all whom it may concern:

Be it known that we, JAMES A. MOORE and JAMES S. CONLEY, citizens of the United States, residing at Rochester and Beaver, county of Beaver, and State of Pennsylvania, have invented a new and useful Improvement in Spacing Mechanism, of which the following is a full, clear, and exact description.

10 The present invention relates to punching and stamping machines, such as are employed for punching and stamping structural iron and steel, and more particularly to spacing mechanism therefor.

15 An object of the invention is to provide a mechanism embodying positive and rigid automatically operated stop means enabling duplicate pieces with accurate spacing to be punched or stamped and having provision 20 for a quick adjustment from one character of spacing to another for different pieces of work.

In the drawings—

25 Figure 1 is a plan view, partly broken away, of a punch press and a spacing mechanism embodying a preferred form of our invention;

Figure 2 is a plan view of the spacing mechanism;

30 Figure 3 is a side elevation of the spacing mechanism;

Figure 4 is a rear end elevation, partly in section, of the spacing mechanism;

35 Figure 5 is a plan view, on a larger scale, of the gripper jaws and associated parts;

Figure 6 is a side elevation of a connecting slide forming an element of the means for operating the gripper jaws;

40 Figure 7 is a perspective view, on a larger scale, of a portion of the rack bar, showing one of the stops carried thereby;

Figure 8 is a plan view showing the gripper jaw locking slide and co-operating dogs;

45 Figure 9 is a section on the line IX-IX of Figure 8;

Figures 10, 11, 11^a and 12 are detail views of the switch and switch operating means associated with the punch press;

50 Figures 13, 14 and 15 are detail views of contact means in the circuit of the electromagnet for operating the gripper jaw locking means, and

Figure 16 is a wiring diagram.

55 In the illustrated embodiment of the invention, the reference numeral 2 designates a horizontal bed plate upon which the work

carriage 3 is mounted, the latter being supported for movement longitudinally of the bed plate by flanged wheels 4 engaging tracks on the upper surface of the bed plate adjacent the longitudinal edges thereof and having their flanges 5 in engagement with said longitudinal edges. The wheels are journaled upon axles 6 with suitable anti-friction bearings 7 interposed between the wheels and axles. The bed plate has depending flanges 8 at its longitudinal edges and depending from the sides of the carriage are brackets 9 which carry rollers 10 engaging the lower edges of the flanges, 70 whereby the carriage is held to the bed plate and prevented from tilting thereon during its reciprocatory movements. Also depending from the sides of the carriage are other brackets 11 which carry anti-friction rollers 12 at their lower ends for engagement with the flanges 8 of the bed plate. These latter rollers guide the carriage in a truly rectilinear path on the bed plate.

Secured by bolts 13 to the forward end of 80 the carriage are the sides 14 of a housing for the gripper jaws and associated operating means. Mounted in the sides 14 and extending between the same is a horizontal pin 15 forming a pivot for a vertically extending 85 gripper jaw operating lever 16. This lever is adapted to be operated either by hand or by a solenoid plunger 17 adjustably connected to the lever by link 18, screw clevis 19 and screw 20, the latter being screwed into 90 the clevis 19 and end of the plunger and held in adjusted position by a lock nut 21.

The lever 16 carries a laterally extending pin 22 at its lower end, which passes through a slot 23 in a connecting slide 24. The slide 24 is pivotally connected at its forward end at 25 to a sliding wedge 26. The wedge slides in contact with the inclined edge of an upward projection 27 on jaw adjustment plate 28 and bears on a fulcrum 29 of rocker insert 30 which moves with the wedge. The rocker insert carries two anti-friction rollers 31 which bear on the movable jaw 32. The jaw 32 is pivoted at its rear end to the jaw adjustment plate 28. This wedging action 100 between the wedge 26 and jaw adjustment plate causes the movable jaw 32 to close in toward the fixed jaw 33 when the slide 24 is advanced by rocking the lever 16 forwardly.

The jaw adjustment plate 28 is mounted 110 for sliding movement transversely of the gripper jaw housing and has a dovetail pro-

jection 34 at its lower side engaging in a dovetail groove in the bottom of the housing. An adjustment screw 35 is screwed into the jaw adjustment plate and extends through the front side 14 of the housing and also through a plate 36 secured to said front side by bolts 37. An adjusting nut 38 engages the screw between the side 14 and plate 36, and a lock nut 39 engages the outer end of the screw. By means of the screw 35 and nuts 38 and 39, the plate 28 can be adjusted to determine the space between the jaws 32 and 33 when the latter are open.

The lever 16 is normally maintained 15 rocked into the forward position shown in Figure 3 by a spring 40. This spring surrounds a stem 41 which is pivoted at its rear end to a stud 42 projecting forwardly from the carriage 3. The stem at its forward end slides in a block 43 pivoted in a slot in the lever 16. The spring bears at one end against the block 43 and at the other end against a clevis portion 44 at the end of the stem.

20 When the lever 16 is released of solenoid action on the plunger 17, the spring 40 rocks it forwardly, thereby causing it to withdraw the wedge 26 through the connecting slide 24. This allows the movable jaw 32 to slide 25 open under the action of the coil spring 45 which surrounds a spring rod 46. The spring rod has one end screwed into an eye 47 swiveled upon the projection 27 of the adjustment plate 28, and said rod slides in 30 a guide eye 48 swiveled upon the movable jaw. The outer end portion of the rod is screw threaded and has nuts 49 mounted thereon. The spring 45 bears at one end against these nuts and at the other end 35 against the eye 48.

The lever 16 is also subject to the action 40 of a coil spring 50 when released from solenoid action on plunger 17. This spring surrounds a spring rod 51 slidably mounted in a guide sleeve 52 carried by a bracket 53. The rear end portion of the rod 51 is flattened and has a slot 54 therein through which extends the upper end portion of a bell-crank lever 55. The other end of the 45 bell-crank lever is screwed into a kick-out cam 56. The kick-out cam extends across the jaw housing and is journaled in the sides thereof. This kick-out cam, under the action of the spring 50, is arranged to bear 50 against the connecting slide 24 and thereby assists the lever 16 in returning sliding wedge 26 to jaw releasing position.

55 Mounted on the carriage 3 is a magnet housing 57, and sliding in said housing is a locking slide 58 for holding the gripping jaws 32 and 33 in closed position when the lever 16 is rocked rearwardly to close the jaws on the work. The locking slide is connected to the lever 16 by a connecting rod 59 and has closely spaced teeth 60 in its side.

60 Mounted for sliding movement transversely of the magnet housing are dogs 61. These dogs, three in number in the construction shown, have teeth 62 so spaced that at least one of them is adapted to mesh with the 70 teeth on the locking slide in any position of the latter. By providing a plurality of dogs and spacing the teeth 62 thereof so that the space between two teeth is not exactly equal to the space between a plurality of the teeth on 75 the locking slide, a very fine adjustment of the locking slide can be obtained. The dogs have stems 63 extending through a flange 64 of the housing 57, and surrounding these stems between the flange and dogs are coil 80 springs 65 which urge the dogs toward the locking slide.

An unlocking lever 66 is pivoted near its lower end upon a pin 67 projecting from a side of the housing 57. This lever is normally held in contact with a stop 68, carried by a pin 69 projecting from the magnet housing, by a coil spring 70. This spring surrounds a stem 71 pivotally connected at one end to the lever 66 and sliding in a bracket 72. The lever is connected by a link 73 to one end of a double crank 74. The crank 74 is journaled in a bearing 75 on the housing 57 and has its other end connected by a link 76 with a grip release latch 77. This latch is in the form of a plate slidably mounted on the magnet housing 57 and adapted to contact with shoulders 78 on the dogs 61 and move said dogs out of engagement with the locking slide when the unlocking lever 66 is rocked away from the stop 68. The unlocking lever is adapted to be attracted by an electromagnet 79 and thereby rocked out of contact with the stop. The electromagnet is momentarily energized, in the manner to be hereinafter described, and when its circuit is broken the spring 70 immediately comes into action and forces the lever away from the magnet, thereby permitting the dogs 61 to move into engagement with the locking slide 58.

65 The bed plate 2 is supported on a suitable base 80 which may be made up of angles and plates riveted and bolted together to form a firm and rigid support for the spacing mechanism. Mounted on the base 80 and extending parallel to but spaced from the rear side of the bed plate is a rack bar 81, supported at approximately the same elevation as the carriage 3. The rack bar has a steel strip 82 positioned in a groove in its upper face, said strip being graduated to any suitable scale. Adjustably mounted on the rack bar are stops. I have deemed it necessary to show only the two end stops 83 and 84 which will always be employed, and one intermediate stop 85, it being understood that any required number of stops may be employed, depending upon the number of holes to be punched in a piece. The

rack bar has a dovetail cross-section and the stops have channels or notches in their under sides to receive said bar.

Referring to Figure 7, it will be seen that the forward end wall of the channel in each stop is inclined for co-operation with the inclined forward edge face of the rack bar. A wedge 86 is inserted in an inclined opening in the rear end portion of the stop, and by engagement with the rear edge face of the rack bar, forces the stop rearwardly to interlock the same with the rack bar. By tapping with a hammer on the lower end of the wedge, the latter can be readily loosened or removed to permit the stop to be adjusted to any desired position on the rack bar. To avoid any possibility of a stop shifting on the rack bar when held in adjusted position thereon by its wedge, the forward edge face of the rack bar is toothed or serrated and the forward end wall of the channel in each stop is similarly toothed or serrated.

The carriage 3 carries a gag 87 for co-operation with the stops on the rack bar to position the carriage for the operation of the punch press. This gag is in the form of a flat bar which slides between rollers 88 in a channel 89 in a guide plate 90. A spring pressed plunger 91 bears against a side of the gag and normally maintains it in the inclined position shown, in which its sides engage inclined edges 92 of the channel. The gag is connected to a solenoid plunger 93 by a link 94, whereby when the solenoid coil is energized, the gag will be retracted so that its nose 95 will clear the stops on the rack bar.

Projecting upwardly from the rear end of the gag 87 is a post 96 having a collar 97 mounted thereon adjacent its upper end. A spring rod 98 has an eye at one end thereof through which the post extends, said end resting on said collar. The rod extends through an angle 99 mounted on the solenoid housing 100 and is surrounded by a coil spring 101 between said angle and a collar 102 on the rod. A collar 103 is mounted on the inner end of the rod and limits outward movement of the gag under the influence of the spring.

Sliding in a channel in a slide box 104 secured to the top of the guide plate 90 is a gag locking slide 105 carrying a roller 106 at its forward end. A plunger 107, acted upon by a spring 108 housed in a cover plate for the slide box, bears on the upper side of the locking slide and presses it against the bottom of the channel in which it slides, whereby the locking slide is frictionally held in any particular position to which it is moved. A gag locking pawl 109 is pivoted in the slide box 104 and is adapted to cooperate with a pin 110 projecting upwardly from the gag for holding the latter

retracted. The gag locking slide has a cam surface 111 on its under side for co-operation with the upper end of the locking pawl. The first stop 83 on the rack bar carries a cam 112 adapted to be engaged by the roller 106 on the forward end of the locking slide, whereby the slide is forced rearwardly until the cam 111 coacts with the upper end of the pawl and rocks said pawl upwardly to disengage its lower end from the pin 110. This permits the spring 101 to project the gag forwardly, so that its nose will strike the stop 83, as the carriage is moved along the bed plate. The last stop 84 carries a cam 113 adapted to be engaged by the roller 106, whereby the locking slide is pulled outwardly to disengage the inclined surface 111 from the upper end of the pawl and permit the latter to drop in front of the pin 110 for holding the gag retracted.

Referring to Figure 1, 114 represents the horizontal bed of a punch press and 115 the punch plunger which slides between guides 116 on the bed. The plunger carries at one end a punch carrier 117 in which is mounted a punch 118 for cooperation with a die block 119. The punch is adapted to punch holes in a strip S moved along on the die block by the spacing mechanism.

Referring to Figures 1, 10, 11 and 12, attached to the plunger 115 is a switch bracket 120, and fixed on the stationary bed of the machine is a switch bracket 121. A lever 122 is mounted on the end of a pin 123 journaled in a bearing 124 on the bracket 120. Fixed on the other end of the pin is a dog 125. A cam 126 is pivoted on the end of a pin 127 carried by the bracket 120 and has an operating handle 128. The cam cooperates with the lever 122, and when the handle 128 is thrown to vertical position, the dog 125 is thrown out of contact with a pin 129 which is carried by a slide 130. This slide reciprocates in a channel in the bracket 121 and has a stem 131 which extends through a bracket 132 and is surrounded between the bracket and slide by a coil spring 133. The pin 129 extends through slots 134 in flanges 135 of a part 121^a secured to the bracket 121 between which flanges the slide 130 reciprocates. A crank 136 is pivoted upon one end of the pin 129, whereby reciprocating movements of the slide 130 actuate the crank and impart rocking movements to the cam disk 137.

The dog 125 has a slotted rearward extension 138 through the slot of which extends a vertical post 139 surrounded by a coil spring 140 which bears upon the under side of the extension and tends to maintain the dog in engagement with the pin 129. The dog 125 is flanged and bears on the bracket 121 as the punch plunger reciprocates.

A switch lever 141 is pivoted upon a pin 142 on the bracket 121 and carries a roller

143 contacting with the periphery of the cam disk 137. The lever is balanced by a spring 144 surrounding a pin 145 carried by the lever and projecting through an angle 146 attached to the bracket 121. The lever has an electrical contact 147 at one end adapted to make contact with an electrical contact 148 mounted on an insulating block 149 on the bracket 121 and urged toward the contact 147 by a coil spring 150. The cam disk 137 has a cam portion 151 in its periphery for cooperation with the roller 143 to move the contact 147 into engagement with the contact 148 when the cam disk is rotated in a clockwise direction (Figure 11). The dog 125 has a beveled forward edge 152 for cooperation with the inclined upper edge of a stationary member 152^a adjustably secured to one of the flanges 135. When the punch plunger moves toward the die block, a shoulder 125^a on the dog 125 engages the pin 129 and rocks the cam disk 137 in a clockwise direction, thereby effecting contact between the contacts 147 and 148. This contact is only momentary, however, as the forward movement of the slide 130 which carries the pin 129 puts the spring 133 under compression. After a slight forward movement of the slide the beveled edge 152 of the dog 125 engages the inclined edge of member 152^a whereby the shoulder 125^a is moved out of engagement with pin 129 whereupon the spring 133 immediately moves the slide 130 rearwardly. This causes the cam disk 137 to be rocked in a counter-clockwise direction to break the contact between the contacts 147 and 148.

Referring to Figures 2, 3, 13, 14 and 15, adjustably mounted on the forward end portion of the part of the base 80 that supports the rack bar 81 is a post 153. This post has a pin 154 projecting from its upper end on which is pivoted a bracket 155. The bracket has an inclined portion 156 to the upper face of which is secured a fiber block 157. This block has one end portion of an inclined plate 158 embedded and secured therein. The inclined portion 156 has a projection 159 for engagement with one edge of the post 153 to limit movement of the bracket 155 and inclined plate 158 in a counter-clockwise direction on the pin 154. Secured to the upper end of the post 153 is another bracket 160. Sliding through an opening in this bracket is a pin 161 having a depending plate 162 at one end which engages a flat side of the bracket 155. A coil spring 163 surrounds the stem between the bracket 159 and plate 162. The plate 158 is normally maintained in the position shown by the spring 163 and by the weight of the plate and bracket 155.

Another pin 164 projects from the upper end of the post 153 and has an electrical contact member 165 pivoted thereon. The

contact member carries a weight 166 which normally maintains it in the position shown in contact with the fiber block 157.

Referring to Figures 2 and 3, the carriage 3 carries a block 167 of insulating material adjacent its rear longitudinal edge. Pivoted upon a pin 168 carried by this block is a switch lever 169. The lever carries a contact roller 170 at one end adapted to travel on the inclined plate 158 and engage the contact member 165 when the carriage is moved to the right. The opposite end of the lever is acted upon by a spring 171 surrounding a pin 172, whereby the lever is normally maintained in contact with an adjustable stop 173.

Referring to the wiring diagram shown in Figure 16, 174 and 175 are the feed lines, controlled by a switch 176, and 177 and 178 are the trolley wires. These trolley wires are engaged by trolleys 179 and 180 carried by the carriage 3 (Figure 4). The feed line 174 connects with the trolley wire 177, through a blowout coil 181 and switch lever 141, while feed line 175 is directly connected to the trolley wire 178. Feed line 174 is also connected to contact member 165. When the carriage 3 is moved to the right and the contact roller 170 on the switch lever 169 makes contact with the contact member 165, a circuit is closed through the coil of the magnet 79, and the unlocking lever 66 is moved to unlocking position, thereby effecting the unlocking of the locking slide 58. When the locking slide 58 is unlocked, the spring 40 immediately rocks the gripper jaw operating lever 16 into the position shown in Figure 3 to open the gripper jaws. As already mentioned, the energizing of the magnet 79 is only momentary as the contact roller 107 drops out of contact with the contact member 165 as soon as said roller reaches the top edge of the inclined plate 158.

Every time that the punch plunger is operated, there is a momentary contact between the electrical contacts 147 and 148, as already explained. The coils of the solenoid plungers 17 and 93 are connected in parallel with the trolley wires 177 and 178 through the trolleys 179 and 180. When the contacts 147 and 148 are closed, these coils are momentarily energized.

Having described in detail the construction of the mechanism embodying our invention, we will now briefly set forth its operation. When it is desired to punch a piece of material, with the carriage 3 at the extreme right of the bed plate, the piece to be punched is placed in contact with the die block 119 and moved along the bed 114 until the end of the piece is positioned between the open jaws 32 and 33 of the spacing mechanism. The end of the piece engages a shoulder 183 on the fixed jaw 33, whereby

the operator, by pushing on the piece, moves the carriage to the left until the gag 87 engages the first stop 83. This arrests the movement of the carriage and workpiece 5 and the gag is swung from its inclined position against the edges 184 and 185 of the channel 89. The rocking of the gag into this new position forces the plunger 91 inwardly and puts its spring 186 under compression. Just before the gag engages the stop 83, the roller 106 on the end of the gag locking slide 105 engages the cam 113 and the gag locking slide is drawn outwardly, thereby permitting the pawl 109 to drop. When the solenoid plunger 93 is withdrawn during the punching of the last hole, the gag is held in retracted position by reason of the engagement of the pawl 109 with the pin 110. The punching of the piece is now completed and the operator will now move the piece and the carriage to the right, this movement being permitted by reason of the gag being held in its retracted position so as to clear the stops on the rack bar. As the carriage approaches its extreme position at the right, the contact roller 170 rides up on the inclined plate 158 and engages the contact member 165. The magnet 79 is thereupon momentarily energized and the unlocking lever 66 operated to unlock the locking slide 58. The spring 40 immediately rocks the lever 16 forwardly to open the jaws. The punched piece can now be removed and another piece to be punched inserted in the open jaws. 10

As the carriage 3 is moved to the left during the punching of the piece, the piece held in the gripper jaws is moved over the bed plate. In order to facilitate this movement of the piece and to reduce wear on the bed plate, anti-friction rollers 188 may be associated with the bed plate 2. These rollers are journaled on shafts 189 supported in the flanges 8 of the bed plate. 15

While we have shown and described a preferred embodiment of our invention, it will be understood that changes may be made in the details of construction without departing from the spirit of the invention or scope of the appended claims. Furthermore, while the invention has been illustrated in connection with a horizontal punch press, it will be apparent that the invention is not limited to use with this character of press but may be used with a vertical press. It will also be understood that the invention is not limited to use with machines for punching holes but may be employed with other types of machines where accurate spacing is desired. The term "punching machine" as employed in certain of the claims is therefore to be interpreted as meaning any metal working machine for performing a series of operations on a work-piece requiring accurate spacing. 20

We claim.

1. Spacing mechanism, comprising a movable carriage, gripper means carried thereby for gripping the work to be operated upon, electromagnetic means for operating said gripper means, and automatic means acting independently of the work being gripped for locking said gripper means in closed position, substantially as described. 25

2. Spacing mechanism, comprising a movable carriage, gripper jaws carried thereby for gripping the work to be operated upon, electromagnetic means for closing said jaws, and automatic means acting independently of the work being gripped for locking said jaws in closed position, substantially as described. 65
3. Spacing mechanism, comprising a movable carriage, gripper jaws carried thereby for gripping the work to be operated upon, spring means for opening said jaws, electromagnetic means for closing said jaws, and automatic means acting independently of the work being gripped for locking said jaws in closed position, substantially as described. 70
4. Spacing mechanism, comprising a movable carriage, gripper jaws carried thereby for gripping the work to be operated upon, electromagnetic means for closing said jaws, automatic means for locking said jaws in closed position, and electromagnetic means for moving said locking means to released position, substantially as described. 75
5. Spacing mechanism, comprising a movable carriage, gripper jaws carried thereby for gripping the work to be operated upon, spring means for opening said jaws, electromagnetic means for closing said jaws, automatic means for locking said jaws in closed position, and electromagnetic means for moving said locking means to released position, substantially as described. 80
6. Spacing mechanism, comprising a bed, a carriage movable thereon, a plurality of stationary stops, a gag on said carriage normally positioned to engage said stops when said carriage is moved in one direction on said bed, electromagnetic means for retracting said gag out of stop engaging position, means for projecting said gag into stop engaging position, means for locking said gag in retracted position, and means associated with one of said stops for moving said locking means to released position, substantially as described. 85
7. Spacing mechanism, comprising a bed, a carriage movable thereon, a plurality of stationary stops, a gag on said carriage normally positioned to engage said stops when said carriage is moved in one direction on said bed, electromagnetic means for retracting said gag out of stop engaging position, means for projecting said gag into stop engaging position, means for locking said gag in retracted position, and means associated with one of said stops for moving said locking means to locking position, substantially as described. 90
8. Spacing mechanism, comprising a bed, a carriage movable thereon, a plurality of stationary stops, a gag on said carriage normally positioned to engage said stops when said carriage is moved in one direction on said bed, electromagnetic means for retracting said gag out of stop engaging position, means for projecting said gag into stop engaging position, means for locking said gag in retracted position, and means associated with one of said stops for moving said locking means to locking position, substantially as described. 95
9. Spacing mechanism, comprising a bed, a carriage movable thereon, a stop support adjacent said bed, a plurality of stops adjustably mounted on said support, a removable wedge member co-operating with each stop and said support for holding the stops in adjusted position, and a gag carried by said carriage for co-operating with said stops, substantially as described. 100
10. Spacing mechanism, comprising a bed, a carriage movable thereon, a stop support adjacent said bed, a plurality of stops adjustably mounted on said support, a gag carried by said carriage and movable thereon into and out of stop engaging position, electromagnetic means for actuating said gag, means for locking said gag in retracted position, and means associated with one of said stops for operating said locking means, substantially as described. 105
11. The combination with a punching machine, of spacing mechanism therefor, comprising a bed, a carriage movable on said bed, gripper means carried thereby for gripping the work to be operated upon, and automatic means effective upon operation of said machine for operating said gripper means, substantially as described. 110
12. The combination with a punching machine, of spacing mechanism therefor, comprising a bed, a carriage movable on said bed, gripper means carried thereby for gripping the work to be operated upon, and electromagnetic means effective upon operation of said machine for operating said gripper means, substantially as described. 115
13. The combination with a punching machine, of spacing mechanism therefor, comprising a bed, a carriage movable on said bed, stationary stops, a gag carried by said carriage for co-operation with said stops, automatic means effective upon operation of said machine for operating said gag, means for locking said gag in retracted position, and means associated with one of said stops for operating said locking means, substantially as described. 120
14. The combination with a punching machine, of spacing mechanism, comprising a bed, a carriage movable on said bed, gripper means carried thereby for gripping the work to be operated upon, a plurality of stationary stops, a gag carried by said carriage for co-operation with said stops, and electro- 125

magnetic means effective upon operation of said machine for operating said gripper means and gag, substantially as described.

15. The combination with a punching machine, of spacing mechanism therefor, comprising a bed, a carriage movable on said bed, gripper jaws carried thereby for gripping the work to be operated upon, electromagnetic means effective upon operation of

10 said machine for closing said jaws, auto-

matic means for locking said jaws in closed position, and electromagnetic means effective upon movement of said carriage in one direction to a predetermined position to move said locking means to released position, substantially as described. 15

In testimony whereof we have hereunto set our hands.

JAMES A. MOORE.

JAMES S. CONLEY.
